Charles Hunt

UNITED STATES PATENT OFFICE.

CHARLES HUNT, OF CHICAGO, ILLINOIS.

PUZZLE.

No. 873,313.

Specification of Letters Patent.

Patented Dec. 10, 1907.

Application filed March 23, 1907. Serial No. 364,206.

To all whom it may concern:

Be it known that I, CHARLES HUNT, a citizen of the United States, residing at Chicago, in the county of Cook and State of Illinois, 5 have invented a Puzzle, of which the following is a specification.

My invention has for its object the production of a figure puzzle, which is designed to be used as an advertising novelty, by 10 printing an advertisement upon the sheet containing instructions for solving the puzzle; or as an amusing and instructive game; or it may be used in the kindergarten department of schools in teaching the children 15 to become familiar with the use of numbers.

In the accompanying drawings forming part of this specification I have illustrated one form of my invention and in these drawings Figure 1 illustrates a complete card with 20 the numbers arranged consecutively as when the puzzle is worked out; Fig. 2 illustrates the small cards with the numbers thereon said cards being cut apart and ready to be assembled.

25 These cards may be made of any desired size and out of any suitable material, preferably card board, all of which are cut about an inch square. A different number is placed upon each side of each card. One of 30 the cards which we will say for the purpose of illustration has the number 33 on one side thereof and the number 10 on the other is cut in two so that on one side of each of the half cards is the figure 3 and on the other 35 sides are the figure one and the cipher respectively.

The numbers in the puzzle run from 1 to 36 and are so arranged that no two cards have the same numbers on both sides, and 40 the numbers are all duplicated excepting the numbers 32 and 36.

When the cards are all cut apart as shown in Fig. 2 they are ready to be assembled as shown in Fig. 1. The assembling is readily 45 done until the figure 32 is reached when it will be found that there is no small card to fill the place. In working out the puzzle we will suppose that in laying down the first half of the cards from 1 to 18 the two numbers 50 4 and 12 are used which have number 26 upon the opposite sides of each one. The two cards having the number 26 on are in

use and one 26 is wanted for the last half of the game, the puzzle will be blocked until No. 26 is found and replaced by another 55 card.

It will be found that by changing around the two halves of the card above referred to that five numbers can be formed, viz. 10, 13, 30, 31 and 33. This is intended to make the 60 game more complicated and for the reason that people try to do things the easiest way, an effort is naturally made to form the right number by changing these half cards into different numbers which can be formed as 65 above explained and placing them in their proper positions, but that will not solve the puzzle. The solution of the puzzle is in separating the two half cards and placing one half on each side of card having No. 23 70 thereon so as to form numbers 32 and 33 in the last row of numbers.

As before explained there is only one No. 32 and one No. 36, and each of these two numbers have No. 1 on the opposite side. 75 In beginning the puzzle by using card No. 1 with 32 on the opposite side, then there is no No. 32 to use when that number is wanted. If the puzzle is begun with the card that has No. 36 on the opposite side there will be no 80 card having 36 to use as the last number, but by forming another 32 with the half cards as above explained then the puzzle can be put together easily.

I claim:

1. A puzzle comprising a set of cards having the numbers from one to thirty six, each of said cards having a different number upon each side thereof, all of said numbers but two being duplicated, and two of said cards 90 being half the size of the remaining cards, substantially as described.

2. A puzzle comprising a set of cards, each of said cards having a different number upon each side thereof, all of said numbers but two being duplicated, two of said cards being half the size of the remaining cards, said half sized cards adapted to be placed upon each side of a whole card to form two new numbers, substantially as described.

CHARLES HUNT.
